G. W. O. MARTIN

MULLING BOX

Filed Sept. 18, 1925

Giles W. O. Martin
By James R. Hodder
Atty.

UNITED STATES PATENT OFFICE.

GILES W. O. MARTIN, OF WEST MEDFORD, MASSACHUSETTS, ASSIGNOR TO AMERICAN SHOE MACHINERY COMPANY, OF EAST BOSTON, MASSACHUSETTS, A CORPORATION OF MASSACHUSETTS.

MULLING BOX.

Application filed September 18, 1925. Serial No. 57,242.

My present invention relates to the working of leather, and more particularly to an improved process and apparatus for treating leather prior to and during the utilization of such leather in the manufacture of articles therefrom.

My invention is particularly applicable to the treatment of leather, such as sole leather, in the manufacture of turned shoes, in which shoes it is, of course, essential that the sole portion be rendered extremely flexible in order that the turning operation be economically and quickly performed. In the preparation of leather, such as soles, for use in turn shoes, it has been necessary to repeatedly subject the sole to the softening influence of a liquid such as water. Although subjected to repeated soaking in water, yet it has been found that the sole does not take up enough water, or the sole is not impregnated to a great enough depth and consequently the moisture retained on what is practically the surface of the leather is quickly evaporated, leaving the leather in even worse condition than it was before the soaking operation. Consequently, in the manufacture of turn shoes, it is necessary to subject the sole to a number of soaking operations and, just before the sole is lasted into the shoe, puts the sole through, in addition to the soaking operation, a breaking operation which renders the leather flexible for a short period of time, usually long enough so that the sewing operation may take place and the shoe then turned. The breakage, because of imperfectly flexed soles, is, however, very high.

In my present invention I have obviated the objections to prior methods of processing the leather and have devised a process which consists in subjecting the sole leather to a humidifying step which renders the sole flexible enough to have performed thereon the usual steps such as rounding and channeling, etc., that take place prior to the breaking operation. After the rounding, channeling, etc., operations have taken place, I preferably send the soles through the Basler tempering machine such, for example, as disclosed in the patent to George Basler, Patent No. 1,036,061 bearing the patent date of Aug. 20, 1912, and after the soles have passed through this machine, and the excess

of moisture drained off, the soles are again placed in my improved humidifying box 55 and kept there until the time for placing the same on the shoe to be lasted. I find that, by the use of my apparatus and my improved process, the soles are in the best condition for performing the various operations and, unless the leather itself is defective, there is no possibility of breakage during the turning operation.

The principal object of my invention, therefore, is an improved process for tempering leather.

Another object of my invention is the improved apparatus for conditioning or tempering leather.

Other objects and novel features of the 70 construction and arrangement of parts comprising my apparatus will be apparent as the description of the invention progresses.

In the accompanying drawings illustrating the preferred embodiment of my invention,

Fig. 1 is a plan view;

Fig. 2 is a front elevation, partly in section;

Fig. 3 is an end elevation, partly in section, and

Fig. 4 is an enlarged detail sectional elevation of a modification of the moistening means illustrated in the remaining figures of the drawings.

Referring to the drawings, 10 designates a box or other suitable water tight enclosure provided at its upper open end with a substantial rim 11, this rim at one side thereof being provided with a plurality of pairs of 90 hinged lugs 12. The number of pairs of hinged lugs 12 may be as many as desired and depends on the size of the unit compartments to be employed and by the overall length of the box or other enclosure 10. 95 The rim 11 is provided with transverse bars 13 acting to subdivide the box into a plurality of chambers equal in number to the number of pairs of hinged lugs 12. To each pair of lugs 12 is hingedly mounted a cover 14, each cover extending forwardly over the top of the rim 11 and adapted to be engaged by a spring locking clip 15 riveted to the front wall of the enclosure 10. Between the under surface of the covers 14 100 and the upper surface of the edges of the

rim 11 and transverse bars 13 is arranged a layer of fibrous material 16 such, for example, as felt. The box or enclosure 10 is subdivided into a plurality of compartments 5 equal in number to the pairs of hinged lugs 12 and the covers 14 by transverse walls 17, the upper edge of these walls being secured to the under surface of the transverse bars 13 and to the bottom of the box 10, as clearly 10 shown in Fig. 2. Secured to the inner face of the end walls of the box 10 and extending transversely of such box is a bar or ledge 18 which lies in the same horizontal plane as similar bars 19 secured to each face 15 of the partition 17. Resting on the bars 18 and 19 are plates 20 of course construction, such as plates of wire mesh, and the plates 20 act as the bottom or supporting surface of material holding chambers. 20 One end of the walls of the box 10 is provided with preferably a pair of perforations 21, such perforations being parallel to each other and located adjacent to the bottom of the box 10. Also the partition walls 17 are 25 provided with like perforations in alignment with the perforations 20 and these perforations in the partition walls 17 are adapted to receive the cylindrical members 22 of asbestos, felt, or any suitable fibrous and porous 30 material, it being understood that the perforations 21 in the end walls are provided for the purpose of inserting the cylindrical members 22 within the box 10. In addition to the material surrounding the perforations 35 in the partition walls 17 acting as a support for the cylindrical members 22, such cylindrical members are further supported by blocks 23 of wood or other suitable material. Each of the perforations 21 is closed by a 40 cylindrical plate 24, such plate being secured to the end wall of the box 10 in any suitable manner. Each of the cylindrical members 22 has inserted therein throughout substantially their entire length a U-shaped pipe 25, 45 one leg of the pipe, and preferably the upper leg, being provided along its top with a plurality of perforations 26. This upper leg of the U-shaped pipe 25 is long enough to extend outward through the perforation in 50 the cylindrical cover 24 and is connected to a U-shaped pipe 27, this pipe, as clearly seen in Fig. 1, also connecting the two U-shaped pipes 25 shown. To the central portion of the U-shaped pipe 27 is connected a riser 28 55 connecting with the bottom of a reservoir 29 supported on a bracket 30 that is secured by riveting or otherwise to the end walls of the box 10. This means consists in the substitution for the cylindrical member 22 of 60 fibrous material a porous porcelain tube 32, this tube being closed at one end, as indicated by the reference numeral 33, and is provided with a plug 34 at its open end. The tube 32 is supported by one or more 65 plugs 35, as clearly shown. Passing through

the plug or cork 34 is a pipe 36 which connects with the interior of the tube 32 and also with the U-shaped pipe 27. In this form of the invention it is designed to have the tube 32 filled at all times with water or 70 other moistening fluid and this fluid is kept under pressure by the column of fluid in the reservoir 30.

My improved apparatus is constructed as above described and, in utilizing this apparatus to practice my improved process, the moistening fluid is placed in the reservoir 30 and such fluid passes through the U-shaped pipe 27 and into either the U-shaped pipe 25 or 26, into the cylindrical member 22 of 80 fibrous material, or into the tube 32 under pressure where it is forced out through the porous porcelain tube 32 and is evaporated from the outer surface of such tube by the air within the box 10. In utilizing the apparatus, I may pile in the various compartments within the box 10 a pile of soles 37 closely adjacent to one another and in stacked relation or may utilize the baseboard 38 having extending upwardly therefrom a plurality of parallelly arranged and spaced pins 39, the space between adjacent pins being filled by the soles 37. In either event, the various compartments within the box 10 are filled with soles 37, the covers 14 shut 90 onto the rim 11 and held in the closed position by the latch 15, and the moisture content of the air within the box 10 gradually becomes greater until, as has been found, the relative humidity varies between 90 and 95%. Preferably the soles are kept in the compartments of the box 10 over night or, should it be necessary, from twenty four to 100 seventy two hours, depending entirely on the temper it is desired to impart to the soles. 105 This preliminary conditioning step is sufficient to allow the various operations of rounding, channeling, etc., to be performed on the soles to the best advantage. After these necessary steps in preparing the sole have been performed, the soles are put through a tempering machine, such as is referred to above, the proper amount of water allowed to flow into the machine, excess moisture drained off, and the soles again placed in the box 10 or covered with a wet cloth and mulled for an hour or more or until in the desired temper. The soles are then put through the breaking operation, shellacked and the edges dyed if necessary, and are replaced in the humidor and sealed tight and left until wanted to place on a 110 shoe.

Having thus described my invention, what I claim as new is:

1. An improved leather conditioning device comprising a box-like casing, means for subdividing the box-like casing into a plurality of separate chambers, means for closing each chamber independently, an absorb-

ent means in said casing, and means for feeding liquid thereto.

2. An improved leather conditioning device comprising a box-like casing, means for subdividing the box-like casing into a plurality of separate chambers, means for closing each chamber independently, and a plu-

rality of absorbent means in said casing, and means for feeding liquid thereto under pressure.

In testimony whereof, I have signed my name to this specification.

GILES W. O. MARTIN.
